UNITED STATES PATENT OFFICE.

CARLISLE H. BALDWIN, OF NEW BRITAIN, CONNECTICUT, ASSIGNOR TO CORBIN CABINET LOCK COMPANY, OF NEW BRITAIN, CONNECTICUT, A CORPORATION OF CONNECTICUT.

DESIGN FOR A MAIL-BOX.

No. 39,569.

Specification for Design.

Patented Sept. 22, 1908.

Application filed May 7, 1908. Serial No. 431,543. Term of patent 7 years.

To all whom it may concern:

Be it known that I, CARLISLE H. BALDWIN, citizen of the United States, residing at New Britain, Hartford county, Connecticut, have invented a new, original, and ornamental Design for a Mail-Box, of which the following is a full, clear, and exact description.

This invention relates to a new, original and ornamental design for mail box.

The design comprises the outline of a mail box body showing a projection across the back of the top, from which the lid depends, which lid is inclined; the box body having curved vertical corners at its front face terminating in the narrow flanges of the back plate; an opening at the bottom of the body portion of peculiar curved outline, within which opening is shown a door of substantially the same transverse section as the body portion and having an inclined bottom, and a gracefully curved hook extending from the bottom and up over the face of the door.

I claim—

The ornamental design for mail box as shown and described.
